UNITED STATES PATENT OFFICE.

BENJAMIN W. TUCKER, OF SOUTH ORANGE, NEW JERSEY, ASSIGNOR TO CORONA
TYPEWRITER COMPANY, INC., A CORPORATION OF NEW YORK.

TYPE-WRITING MACHINE.

1,281,103.

Specification of Letters Patent. Patented Oct. 8, 1918.

Application filed July 15, 1916. Serial No. 109,466.

To all whom it may concern:

Be it known that I, BENJAMIN W. TUCKER, a citizen of the United States, and a resident of South Orange, county of Essex, and State 5 of New Jersey, have invented certain new and useful Improvements in Type-Writing Machines, of which the following is a full, clear, and exact description.

This invention relates more particularly to 10 platen carriages of front strike or other visible writing machines.

One of the principal objects of the invention is to provide a platen carriage which may be extended various distances, to adapt 15 the same to hold work sheets of various lengths or widths, and much wider than the ordinary or normal length of the carriage, and which is so constructed that the lines of writing may be of the ordinary length 20 or of an abnormal length, according to the width of the work sheet, and such additional or abnormal length of lines may be written without shifting the work sheet, and without requiring the platen to be extended or 25 platens of relatively different lengths provided.

Another object of the invention is to provide a carriage having a platen of normal size, and which is automatically positioned 30 to take the impact of the type while writing, whether the lines of writing are of the usual or normal length, or of an abnormal length.

Other objects of the invention are to provide simple and efficient means whereby the 35 carriage may be extended different lengths, and held in such extended position; to provide simple means whereby an extended carriage or one of normal length may be made to travel along a bed without extending said 40 bed; to provide means whereby the carriage may have the various parts coöperating therewith, whether in a normal or in an extended condition, and without any disconnection or disarrangements of the parts; 45 and to provide simple means whereby two sets of dog carriers may coöperate with the single rack, either at the same time or at different times, to adapt a long or a short carriage to travel along a relatively short 50 bed.

A further object of the invention is to provide simple and efficient means for line spacing the platen, either in its normal or in its extended condition.

55 A still further object of the invention is

to provide simple and efficient means whereby the carriage may be positively held in any of its adjusted positions; and to provide a construction whereby the carriage base or parts may be telescoped or extended 60 at will.

A further object of the invention is to provide a carriage which is adapted for use either on small portable visible typewriters, or adapted for use in connection with writing machines of various kinds and constructions. 65

With these and other objects in view, the invention will be hereinafter more particularly described with reference to the accompanying drawings, which form a part of this application, and will then be pointed out in the claims at the end of the description. 70

In the drawings, Figure 1 is a front elevation, partly broken away, and partly in section, of one form of carriage embodying the invention. 75

Fig. 2 is an elevation looking at one end of the carriage.

Fig. 3 is an elevation looking at the opposite end of the carriage. 80

Fig. 4 is an elevation showing the carriage in one of its extended positions.

Fig. 5 is an inverted plan, partly broken away, of the carriage bed and part of the support. 85

Fig. 6 is a plan view, partly broken away, of one end of the carriage.

Fig. 7 is a sectional plan of the part of the carriage shown in Fig. 6, in an extended 90 condition.

Fig. 8 is a rear elevation, partly broken away, of the end of the carriage shown in Figs. 6 and 7.

Fig. 9 is a view similar to Fig. 8, except 95 that the carriage is shown in an extended condition.

Fig. 10 is a transverse section through the carriage, taken on the line X—X of Fig. 1.

Fig. 11 is a transverse section through the carriage, taken on the line XI—XI of Fig. 1. 100

Fig. 12 is a fragmentary vertical section, showing one means for extending or collapsing the carriage.

Fig. 13 is a view similar to Fig. 12, except 105 that the parts have been extended.

Fig. 14 is a fragmentary plan view of part of the means shown in Figs. 12 and 13, having particular reference to the part for releasing the paper apron and pressure roll. 110

Fig. 15 is a section taken on the line XV—XV of Figs. 13 and 14.

Fig. 16 is a fragmentary section of one of the carriage ends showing a part of the means for supporting part of the feed rolls.

Fig. 17 is a view similar to view 16, except that the parts are shown in an extended position.

Fig. 18 is a fragmentary section of a part of the platen in a normal condition.

Fig. 19 is a transverse section of Fig. 18.

Fig. 20 is a view similar to Fig. 18, except that the parts are shown in an extended condition.

Fig. 21 is a view partly diagrammatic, showing the platen and part of the carriage in an extended condition, illustrating how the platen may move with the carriage, and after traveling a certain distance be held stationary while the carriage continues to travel.

Fig. 22 is a fragmentary elevation showing the position of the parts when the platen is to be automatic in its action and long lines of writing are to be impressed upon the work sheet.

Fig. 23 is an elevation showing the parts illustrated in Fig. 21, with the carriage in position to cause the platen to be held in a relatively fixed position.

Fig. 24 is a view similar to Fig. 23, except that the parts are in a different position, the carriage having traveled with the paper a certain distance independent of any movement of the platen; and

Fig. 25 is a fragmentary perspective view, partly broken away, of the supporting means shown in Fig. 16.

The bed 10 may be supported in any suitable way, and adapted to travel along said bed or other support is a carriage which has end plates or brackets 12 and 13, and said end plates or brackets are connected together by an extensible and telescopic base

14. This base 14 comprises an outer part or member 15, and two slidable members 16 and 16^a, one of which is secured to the end bracket 12, and the other to the carriage end bracket 13, and both of which members 16 and 16^a are held to slide within the outer member 15. The outer member 15 is of a box-like form, and comprises a top portion 17, and a bottom portion 18, rigidly held together, and serves to inclose the inner mem-

bers 16 and 16^a when in the normal and non-extended condition of the carriage. The slidable and telescopic members 16 and 16^a are similarly constructed and are substantially U-shaped in cross section, and are adapted at the sides and top portion thereof to bear against and slide along the walls of the base member 15. The outer member 15 of the base is provided with L-shaped brackets 19, the lower portion of which is adapted to engage track surfaces 20 along the front

and rear edges of the bed 10, and adapted to travel along said track surfaces are rolls 21 held to the ends of shafts or rods 22 and by which the carriage is adapted to be held to travel lengthwise of the bed, there being any desired number of these rolls 21 to support the carriage properly in its letter space travel.

A bracket 23 is arranged substantially midway of the outer base member 15, and is secured to the upper portion thereof by screws 24 or otherwise. The bracket 23 has a pendant portion 25, which is provided with a threaded aperture. A two part screw 26 has one part 27 exteriorly threaded, and is adapted to engage the threaded aperture in the part 25 of the bracket 23. This part 27 is tubular in form, and is provided with an internal thread, which is adapted to be engaged by the threaded end of the screw part 28. The screw part 28 is held to the carriage end bracket 12, and the screw part 27 is rotatably held against lengthwise relative movement in the carriage end bracket 13, but in such a way as to be rotatable therein. The screw part 28 has its outer end reduced, and is held against rotary movement in the end bracket 12 by means of a screw 29 and washer 30, or otherwise, and the screw part 27 is held to rotate with the rod 31 which extends through the carriage bracket 13, and has on the outer end thereof a knob 32 provided with a knurled head, by means of which the screw part 27 may be rotated. The screw part 27 has a right hand thread and the screw part 28 a left hand thread, and the pitch of the threads of the two parts is in this case two to one. The bracket 23 with the part 25 extends through the outer inclosing member 15 of the carriage base and serves to hold the said base relatively stationary, the slide members 16 and 16^a being suitably recessed or formed to permit the two part screw to engage the part 25 of the bracket 23, without interfering with said bracket.

It will be evident, that by reason of the two part screw and its engagement with the part 25 of the bracket, and by reason of the base part 16 and 16^a being held to the end brackets 12 and 13 respectively, that by rotating the screw part 27 by means of the knob 32 the two part screw will have the parts thereof forced apart when the knob 32 is rotated in one direction, thus extending the carriage end plates 12 and 13 and moving therewith the carriage base parts 16 and 16^a, while a reverse movement of the knob 32 will cause the two carriage end plates and the base parts to be collapsed and moved toward each other to the position shown in Figs. 1 and 12.

The platen 33 is mounted to rotate in the carriage, and is adapted to move with the carriage in its normal condition, or to move

with the carriage, or held stationary during the movement of the carriage when the latter is in an abnormal or extended condition. This platen comprises a tubular body 34, 5 which may be made similar to the ordinary platen, or in any preferred way, and is mounted to rotate with an axis or shaft 35. The axis or shaft is extensible and is formed in two parts 36 and 37, so as to slide relatively with respect to each other. One of the members, as 36, is rotatably held at its outer end in the carriage end piece 12, and the platen axis member 37 is rotatably held in the carriage end piece or bracket 13. The 10 two members 36 and 37 are semi-cylindrical at one portion thereof, and have straight portions, as 38, which slide upon each other, and by reason of such portions the two members 36 and 37 of the platen shaft or axis 15 will always rotate in unison. The platen body 34 is slidably held to the shaft or axis member 37 by making the part 37 square or otherwise, so that a relative lengthwise movement may take place between the body 34 and the axis members 36 and 37, and still the axis members and platen body 34 be made to rotate together. At the outer end of the axis or shaft member 37 is a pinion 40, having a sleeve portion through which the 20 platen shaft member 37 passes. The shaft members 36 and 37 may be connected together by a telescopic bar or member 41. This bar or member comprises two parts, 25 42 and 43, and each have an overlapping substantially U-shaped part 44, which permits one part of said bar to slide relatively to the other to partake of the extended or collapsed condition of the carriage end plates or brackets 12 and 13 of the carriage base, said parts 30 42 and 43 being adapted to pass through openings in said end plates 12 and 13 respectively. The members 42 and 43 of the bar 41 have parts 45 and 45^a respectively, one of which is held to the outer end of 35 the platen axis shaft 36 and the other to the platen axis shaft part 37. The part 45 of the bar 41 has a downwardly projecting portion or stop 46, and the part 45^a a projecting portion or stop 46^a and these stops 40 46 and 46^a are adapted to engage parts on the carriage bed 10, when it is desired to write lines longer than the usual travel of the carriage. In this case the parts 46 and 46^a do not directly engage the carriage bed, but 45 each engage an upwardly projecting finger 47 on a slide 48, located at each end of the carriage bed 10. This slide is shown best in Figs. 5 and 21 to 24 inclusive, and is adapted to be positioned to cause the parts 46 and 46^a to engage the fingers 47 or to prevent such engagement for a purpose to be presently described. The slides 48 are in the form of a plate, having slots in the body, through which pass screws 49, and are each 50 provided with a finger piece 50 by which

each slide 48 may be moved at the will of the operator.

The slides 48 are moved so as not to engage the projecting parts 46 and 46^a when the carriage is in its normal non-extended condition, but when extended, as shown in Figs. 21 to 24, the slides are positioned so that the upwardly projecting portions 47 are in position to be engaged by the said parts 46 and 46^a. The carriage end pieces 12 and 13 are 75 extended by means of the two part screw on the rotation of the knob 32, as already described, and the carriage has its letter space movement controlled by suitable escapement, one form of which will be presently described. When the carriage is moved to the right to begin a line of printing the part 46 at the left of the carriage will engage the part 47 on that side of the bed 10, as shown in Fig. 21, which permits the carriage to move to the position shown in Fig. 21, the bar members 42 and 43 being held at this time to permit relative movement of the carriage end pieces or brackets 12 and 13. During the letter space movement of the carriage 80 the writing may be continued throughout the entire length of the platen, all parts moving together and when near the end of the platen the stop 46^a on the right hand side will engage the projection 85 47 on that side of the carriage bed, and will hold the platen against movement. The subsequent printing will be at the same printing point on the platen, and during the letter spacing movement of the carriage the 90 carriage with the end plates will be moved from the position shown in Figs. 21 and 23 to that shown in Fig. 24. Thus the printing of a line much wider than the carriage bed and the normal size of the carriage takes 95 100 place automatically, without using interchangeable platens, or a sectional platen, and without the necessity for shifting the paper. The work sheet during the printing operation is not held directly about the platen 105 and to the same, as is usually the case, but said work sheet is held above and below the platen so as to rest simply against the face of the platen along the printing line, as it is necessary under the construction 110 shown, that the work sheet, when the carriage is extended and long lines wider than the usual size of the carriage are to be printed and during the time that the platen is held stationary, travels with the carriage 115 relatively to the platen. In the construction shown, the work sheet is held beneath the platen between pressure or feed rolls 51 and 52, and above the platen the work sheet is held between the paper finger rolls 53. 120 125 and the larger rolls 54, and intermediate the rolls is a pressure finger 54^a for forcing the work sheet at the printing point against the platen, said pressure finger being held to a type aliner 54^b or otherwise. The rolls 130

53 are held to paper fingers 55, which are adjustable along the bar 55^a, or otherwise, as preferred, said paper fingers having a substantially U-shaped part 56 to fit over 5 said bar 55^a to hold the same frictionally in any one of its adjusted positions, according to the width of the work sheet used. The rolls 52 and the rolls 54 comprise a plurality of sections or members. These 10 members are held upon square rods or shafts 57 and said shafts are supported in brackets or arms 58. The arms for the rolls 54 extend upwardly and forwardly, and the arms for the rolls 52 extend downwardly and forwardly and said arms are held to a sectional supporting bar or support 59. This support or bar comprises a plurality of sections which may be rectangular in form so that they will not rotate relatively. The 15 sections of the supporting bar 59 correspond in number to the number of sections of the rolls 52 and 54, and each section of the bar or support 59 has projecting outwardly from each end thereof one of a 20 pair of arms 58, so that said arms will be arranged in pairs and each pair being adapted to support its individual pressure roll section, there being a bushing or collar at the end of each roll section which is held 25 to one of the arms 58 and assists in guiding the rods 57. A lazy tong movement 60 is provided to maintain the sections of the rolls 52 and 54, and the sections of the bar or support 59 in their proper relative positions, and to cause said rolls to be moved 30 toward and from each other during the extension or collapsing of the carriage. The lazy tong 60 has the usual links operatively connected together, and one end of the lazy 35 tong is connected at 61 to a collar or a projection on the carriage end plate 13, and the opposite end is similarly connected to the carriage end plate 12. The lazy tong links are held at 62, Figs. 8 and 9, to one of the 40 outer bar sections, and at 63 to the intermediate bar section. In Figs. 8 and 9 only one end of the carriage is shown, but the opposite end thereof is similarly constructed and the two parts of the lazy tong are connected by long horizontally arranged links 45 64. This arrangement will cause the sections of the support 59 and the pressure rolls 52 and 54 to be spread apart, the intermediate section of the support 59 and the 50 intermediate pressure rolls remaining normally centrally of the carriage in both its normal collapsed condition and in its abnormal extended condition. The construction of the sectional bar or support 59 is 55 best shown in Figs. 6, 7, 10, 16 and 17. Each section comprises a square tubular part 65, to the center one of which is secured a square tube 66 which projects from opposite sides of the central part 65 so as to enter

the adjacent sections and form a guide 65 therefor. At each end of the carriage is a normally stationary square bar 67, the inner end of which slides within the opening of its adjacent section and also projects onto the center section. The pressure rolls 51 co-operate with the sections of the lower rolls 52, and said rolls 51 are mounted to rotate upon the forward portion of the paper apron 68. This paper apron is of a plate like form common to carriages of different kinds 70 of writing machines, and is normally forced in one direction by one or more springs 69 to cause the work sheet to be gripped between the rolls 51 and the sections of the roll 52, so that when said rolls are rotated, 75 as will be presently described, the work sheet will be moved past the platen for the different lines of printing. As shown, there are two rolls 51, each separately journaled in the paper apron and said rolls are each 80 of such a length as to co-operate with two of the lower pressure roll sections, whether the carriage is in the normal condition or in an extended condition.

The pressure rolls 51 may be released in 85 any suitable way. As shown, a finger 70 is pivotally held to the upper portion of the bracket 23, and adapted to engage said finger 70 is a square rod 71. The rod 71 has a sliding connection with the finger 70, and is 90 of such a length as will permit the extension of the carriage without disengagement of the rod from said finger. At the outer end of the rod 71 is a finger lever 72, by which the rod 71 may be rocked, thus causing the finger 70 to engage the paper apron and move the same against the tension of the spring 69, and thereby force the roll 51 away from the pressure roll 52, thus freeing 95 the work sheet to permit the same to be adjusted or for other reasons, as usual in machines of this kind.

As a means for controlling the letter feed movement of the carriage along the bed 10 I provide two dog carriers 73 and 74, which 110 are adapted to co-operate together or individually with a rack 75 mounted upon the carriage base. The dog carriers 73 and 74 are similarly constructed. Each of the dog carriers is pivoted at 76 at one end, and may be guided at its other end in a bracket 77. On each arm or carrier are arranged two dogs, one of which may be a fixed dog and the other a loose dog, and both of which are adapted to co-operate with the rack to permit 115 the carriage to move a letter space each time the escapement is tripped, as is usual, it being understood that any suitable escapement means may be employed. Each dog carrier is normally forced in one direction by a spring 78, and in the opposite direction by a tappet 79. There are two tappets 79, one 120 for each escapement carrier, and said tappets 125

are adapted to engage projections 80 on side carriers. The tappets 79 form extensions of a rocking bar 81 which is operatively connected to the universal bar. As shown, the 5 rocking bar forms a part of the universal bar frame, and may be operated in substantially the same way as in the Corona typewriter, and during each rocking movement is adapted to trip the escapements, the carriage 10 being under the tension of a spring in a drum 82, from which extends a cord or other flexible connection 83, as is usual in the Corona typewriter and other writing machines. 15 The rocking frame 81 may be made to vibrate the ribbon to and from the printing point, or permit the same to remain inactive and the carriage and parts coöperating therewith may be mounted upon a foldable 20 support, as in the Corona typewriter, but the invention is not limited to such features nor to the particular type of machine with which the invention may be used.

The platen may be rotated and line spaced 25 in any desired manner. As one means, a gear 84 is mounted to rotate on the outer end of one of the rods of the sectional support 59. The gear is provided with a knob 85 to rotate the same, and said gear is adapted 30 to mesh with the pinion 40 on the platen shaft or axis, a pinion 86 on the shaft of the pressure rolls 52, and a pinion 86^a on the shaft of the sectional pressure roll 54, so that the said shafts will rotate in unison, thus 35 assisting in the feed of the work sheet manually in either direction, at the will of the operator.

A line spacing means is mounted at the end of the carriage opposite the knob 85. 40 A large gear 87 similar to the gear 84 is mounted to rotate axially on the supporting bar 59, and held to move with the gear is a ratchet wheel 88. The teeth of the ratchet wheel 88 are adapted to be engaged by a 45 pawl 89, and said pawl 89 is pivoted to a lever 90, and is normally forced into engagement with the teeth of the ratchet wheel 88, by means of a spring 91. The lever 90 is pivotally held to move independently of 50 the ratchet wheel, and the gear 87, and may be made to move said gear various distances, such distances corresponding to one, two, or three line spaces, or otherwise, by means of an adjustable stop 91^a shown in dotted lines 55 in Fig. 2 and operated by a knob 91^b, or in any other desired way. The gear 87 meshes with the gear or pinion 92 on the shaft of the sectional roll 54, and said gear 87 also meshes with the gear 93 on the shaft of the sectional 60 roll 52, thus rotating both rolls in unison, and forcing the work sheet about the platen for line spacing in the usual way.

The invention will be readily understood from the foregoing description, when taken

in connection with the accompanying drawings. If the carriage is in the condition shown in Fig. 1, which is the normal position of the parts when writing upon work sheets of the usual width, the carriage in this case may be moved for letter spacing 65 along the bed 10 in the usual way. If, on the other hand, it is desired to print or write lines on work sheets much wider or wider than the usual width of work sheets, the carriage in such case is extended by rotating the knob 32, so as to force the carriage end plates 12 and 13, and the parts mounted thereon and connected thereto in the manner already described, and to a distance corresponding to the width of the work sheet to 70 be used with the carriage when thus extended. As thus extended the work sheet may be line spaced and adjusted as already explained, and the carriage will travel along the bed controlled by its feed mechanism. 75 When the carriage is forced to the right, looking from the front of the machine, the platen shaft part 36 is held against such movement by the engagement of the part 46 at the left of the machine with the projection 47 on the carriage bed 10, thus permitting the carriage end plate 12 to move away from the part 45 a distance corresponding to the extension of the carriage. During the letter printing movement the 80 carriage with the platen will move together for substantially the entire length of the platen, if the lines are to be written of a length greater than the length of the platen, until the projection or part 46 at the right 85 of the machine engages the part 47 on the same side of the machine when the platen will be held against further movement. The carriage with the work sheet may continue to move, at which time the carriage end plates 90 will slide upon the parts 36 and 37 of the platen shaft or axis from the position shown in Fig. 23 to the position shown in Fig. 24, during which time the printing will be upon the same part of the platen for the 95 reason that the platen during this additional writing or extension of line printing is held stationary.

It will be evident from the foregoing that the carriage may write lines on a work sheet 115 of different lengths, and when the carriage is extended the writing may be continued entirely automatic, without any attention being paid whatever to the work sheet further than that required when writing the 120 ordinary normal and usual length of lines.

In the drawings, different parts usually coöperating with the carriage are shown, such as margin stops, scale, type aliner, and other features, but such parts are shown for the 125 purpose of illustrating how these parts may be arranged and mounted to adapt them to the form of platen carriage shown and de-

scribed herein, but such features, as well as many of the other parts, may be of any suitable construction, and arranged in any desired way.

5 Having thus described my invention, I claim as new and desire to secure by Letters Patent:—

1. In a typewriting machine, the combination of a carriage bed, a carriage adapted 10 to travel along said bed having an extensible base and end plates carried by said base, means whereby the end plates and base may be extended or the end plates moved toward each other, a platen, feed 15 means for the work sheet, and means for supporting the platen and including means to cause the platen to travel with the carriage or to be held stationary during a part of the travel of said carriage.
2. In a typewriting machine, the combination of a support, a carriage adapted to travel along said support having an extensible base and end plates carried by said base, means whereby the end plates and base 25 may be extended or the end plates moved toward each other, a platen, and means enabling the platen to travel with the carriage or to be held stationary during a part of the travel of said carriage.
3. In a typewriting machine, the combination of a support, an extensible carriage adapted to travel along said support, a platen, feed means for a work sheet, and means enabling the platen to receive the impact of the type when the carriage is in an 30 extended condition.
4. In a typewriting machine, the combination of a carriage bed, a carriage adapted to travel along said bed having an extensible base and end plates carried by said base, means whereby the end plates and base may be extended or the end plates moved toward each other, a platen, and automatic means enabling the platen to 40 travel with the carriage or to be held stationary during a part of the travel of the carriage.
5. In a typewriting machine, the combination of a support, an extensible carriage 50 adapted to travel along said support, a platen, feed means for the work sheet, and automatic means adapting the platen to travel with the carriage or to be held stationary during a part of the travel of the carriage.
6. In a typewriting machine, the combination of a support, a carriage adapted to travel along said support, having means whereby said carriage may be lengthened 60 or shortened, a platen mounted in the carriage, and means whereby lines of greater length than the platen may be written upon a work sheet supported by the carriage.
7. In a typewriting machine, the combi-

nation of a support, a carriage adapted 65 to travel along said support, having means whereby said carriage may be lengthened or shortened, a platen mounted in the carriage, and automatic means enabling lines of greater length than the platen to be written upon a work sheet held in front of the platen.

8. In a typewriting machine, the combination of a support, a carriage adapted to travel along said support, having means 75 whereby said carriage may be lengthened or shortened, a platen roll mounted in the carriage, and automatic means including means to hold the platen stationary whereby lines of greater length than the platen may 80 be written upon a work sheet held in front of the platen.

9. In a typewriting machine, the combination of an extensible carriage, a platen mounted in the carriage, and means whereby writing of greater length than the platen may be written upon a work sheet held about said platen, said means including means for holding the platen stationary during a part of the travel of said carriage.

10. In a typewriting machine, the combination of an extensible carriage, a platen mounted in the carriage, and automatically acting means enabling writing of greater length than the platen to be written upon a 95 work sheet supported by said carriage.

11. In a typewriting machine, the combination of an extensible carriage, a platen mounted in the carriage, and means whereby writing of greater length than the platen may be written upon a work sheet held about said platen, said means including engageable stops for holding the platen stationary during a part of the travel of said carriage.

12. In a typewriting machine, the combination of a support, a carriage adapted to travel along said support, a platen mounted in the carriage, means for extending the carriage without extending the platen, work sheet feeding means located above and below the platen, and means for enabling the carriage to have a greater travel than the platen.

13. In a typewriting machine, the combination of a support, a carriage adapted to travel along said support, a platen mounted in the carriage, means for extending the carriage without extending the platen, and means for enabling the carriage to have a 115 greater travel than the platen.

14. In a typewriting machine, the combination of a support, a carriage adapted to travel along said support, a platen mounted in the carriage, means for extending the carriage, work sheet feeding means, and means for enabling the carriage to have a 125 greater travel than the platen.

15. In a typewriting machine, the combination of a support, a carriage adapted to travel along said support, a platen, and means enabling the carriage to travel a greater distance than the platen. 65
16. In a typewriting machine, the combination of a support, a carriage adapted to travel along said support, a platen, and automatic means enabling the carriage to travel a greater distance than the platen. 70
17. In a typewriting machine, the combination of a support, an extensible carriage adapted to travel along said support, a platen, and automatic means enabling the carriage to travel a greater distance than the platen. 75
18. In a typewriting machine, the combination of a support, a carriage having a telescopic base and carriage end plates held to different parts of said base, a platen, feeding means for work sheet, and a screw having a plurality of parts for moving the carriage end plates toward or from each other. 80
19. In a typewriting machine, the combination of a support, a carriage having extensible parts, a platen mounted in the carriage, and a screw for moving the carriage extensible parts. 85
20. In a typewriting machine, the combination of a support, a carriage having a telescopic base and carriage end plates held to different parts of said base, a platen, and a screw for moving the carriage end plates toward or from each other. 90
21. In a typewriting machine, the combination of a support, a carriage adapted to travel along said support, end plates, means whereby the end plates may be moved toward and from each other, a platen, sectional feed rolls, a paper apron, a sectional support for the sectional feed rolls, and means for moving the sectional feed rolls and sectional support therefor with the movement of the carriage end plates. 95
22. In a typewriting machine, the combination of a support, a carriage adapted to travel along said support, end plates, means whereby the end plates may be moved toward and from each other, a platen, and means for holding a work sheet near but independent of the platen. 100
23. In a typewriting machine, the combination of a support, a carriage adapted to travel along said support, end plates, means whereby the end plates may be moved toward and from each other, a platen, sectional feed rolls, a sectional support for the sectional feed rolls, and means for moving the sectional feed rolls and sectional support therefor with the movement of the carriage end plates. 105
24. In a typewriting machine, the combination of a support, a carriage adapted to travel along said support, end plates, means whereby the end plates may be moved toward and from each other, a platen, and sectional support for the sectional feed rolls, a sectional support for the sectional feed rolls, and means for moving the sectional feed rolls and sectional support therefor with the movement of the carriage end plates. 110
25. In a typewriting machine, the combination of a support, a platen, and a carriage in which the platen is mounted, and means for causing said carriage to travel along said support with the platen or independently thereof. 115
26. In a typewriting machine, the combination of a support, a platen, and an extensible carriage in which the platen is mounted, and means for causing said carriage to travel along said support with the platen or independently thereof. 120
27. In a typewriting machine, the combination of a support, a carriage having end plates and means whereby the end plates may be moved toward and from each other, a platen rotatably held in said end plates, extensible means for supporting the platen, an extensible bar connecting the extensible supporting means of the platen together, and means carried by said bar adapted to engage said support and positioned to permit the carriage and platen to travel together and to cause the carriage to travel independently of the platen. 125
28. In a typewriting machine, the combination of a support, a carriage adapted to travel along said support and having end plates and means whereby the end plates may be moved toward and from each other, a platen rotatably held in said end plates, extensible means for supporting the platen, an extensible bar connecting the extensible supporting means of the platen together, stops on the support, and stops carried by said bar adapted to engage said stops on the support and positioned to permit the carriage and platen to travel together and to cause the carriage to travel independently of the platen. 130
29. In a typewriting machine, the combination of a support, a carriage having end plates and means whereby the end plates may be moved toward and from each other, a platen rotatably held in said end plates, extensible means for supporting the platen, extensible means connecting the extensible supporting means of the platen together, and means carried by said extensible means adapted to engage said support and positioned to permit the carriage and platen to travel together or the carriage to travel independently of the platen. 135
30. In a typewriting machine, the combination of a platen, an extensible carriage having end plates, an extensible shaft forming an axis for the platen and rotatably held in said end plates, means for rotating said extensible shaft and platen, a support for the carriage of less length than the carriage. 140

when extended, and means enabling the carriage to have a greater travel along its support than the length of said platen.

31. In a typewriting machine, the combination of a platen, an extensible carriage, an extensible shaft forming an axis for the platen and rotatably held in said carriage, means for rotating said extensible shaft and platen, a support for the carriage, and means enabling the carriage to have a greater travel along its support than the length of said platen.

32. In a typewriting machine, the combination of a platen, an extensible carriage having end plates, an extensible shaft forming an axis for the platen and rotatably held in said end plates, means for rotating said extensible shaft and platen, a support for the carriage of less length than the carriage when extended, and means enabling the carriage to have a greater travel along its support than the length of said platen while the latter is held stationary.

33. In a typewriting machine, the combination of a support, a carriage adapted to travel along said support and having an extensible base and end plates supported by parts of said base, a platen, sectional rolls located above and below the platen, a sectional support comprising a plurality of

parts substantially rectangular in cross section and forming supporting means for the sectional rolls, a lazy tong connection between said parts, and means for moving the end plates toward and from each other.

34. In a typewriting machine, the combination of a support, a carriage adapted to travel along said support and having an extensible base and end plates supported by parts of said base, a platen, sectional rolls mounted in the carriage, and a lazy tong connection between said rolls, and means for moving the end plates toward and from each other.

35. In a typewriting machine, the combination of a support, a carriage adapted to travel along said support and having an extensible base and end plates supported by parts of said base, a platen mounted in said end plates, sectional rolls forming means to hold and feed a work sheet, a sectional support comprising a plurality of parts forming supporting means for the sectional rolls, a lazy tong connection between said parts, and a screw for moving the end plates toward and from each other.

This specification signed this 13th day of July, A. D. 1916.

BENJAMIN W. TUCKER.
